Primary Examiner—Mark A Goodwin(74) *Attorney, Agent, or Firm*—Waddey & Patterson, P.C.; Lucian Wayne Beavers(57) **CLAIM**

A road milling machine, as shown and described.

DESCRIPTION

FIG. 1 is a side perspective view of a road milling machine showing my new design;

FIG. 2 is a side elevational view of the road milling machine of FIG. 1;

FIG. 3 is a side elevational view of the road milling machine opposite to the side shown in FIG. 2;

FIG. 4 is a top plan view looking downwardly in FIG. 3;

FIG. 5 is a bottom plan view looking upwardly in FIG. 3;

FIG. 6 is an end elevational view looking from left-to-right in FIG. 3; and,

FIG. 7 is an end elevational view looking from right-to-left in FIG. 3.

The broken lines in FIGS. 1, 3 and 7 are shown to define boundaries around portions of the article which are not part of the claimed design.
